UNITED STATES PATENT OFFICE.

JAMES F. COLLINS, OF SWISSVALE BOROUGH, PENNSYLVANIA.

PROTECTIVE MECHANISM.

1,374,636.

Specification of Letters Patent. Patented Apr. 12, 1921.

Application filed August 30, 1920. Serial No. 407,030.

To all whom it may concern:

Be it known that I, JAMES F. COLLINS, a citizen of the United States, and residing in the borough of Swissvale, in the county of Allegheny and State of Pennsylvania, have invented or discovered new, useful, and Improved Protective Mechanism, of which the following is a specification.

My invention consists in a new and improved protective device for banks and other places of business wherein money or other valuables are exposed to view.

Thus, for instance, the paying teller of a bank has during business hours relatively large amounts of money on his counter protected usually only by the metal caging with which banks are provided. Instances are not rare where banks and other places of business have been robbed by supposed customers suddenly pointing firearms at the teller and compelling him to throw up his hands or to pass out the money or valuables displayed.

The object which I have in view is the provision of means whereby the money or valuables displayed may be protected and such unlawful taking prevented.

Generally speaking, my invention consists of a safe, preferably located at one side of the teller's window, and provided with an opening in its top through which upwardly extends a cage preferably closed at its back and sides with metal bars or lattice and provided with a solid top and bottom, said top being made of safe steel and of proper dimensions to fit in the opening of the safe when the cage is dropped. When the cage is raised, its bottom, which may be of wood or other material to match the permanent counter, is above or flush with the top of the safe and forms the money board or counter upon which the money or other valuables are placed.

Means are provided for holding the cage in its raised position which means are releasable by the teller or other clerk, who, when an attack is made, steps on a foot treadle or otherwise operates the release in an inconspicuous manner. Thus, the cage is caused to drop within the safe, so that it cannot be raised or its contents reached until the door in the front of the safe, guarded by a suitable combination or time lock, is opened.

Means are provided for locking the cage in its dropped position, so that no prying

or other attempts from above will result in raising the cage.

Means are also provided for automatically locking the cage in its dropped position, said locking means being provided with release mechanism which can only be gotten at by first unlocking the safe door.

I also provide automatic alarm means, preferably of the audible type, for giving notice of the attack, either generally in the banking room or at the police or protective headquarters.

Other novel features of construction and arrangement of parts will appear from the following description.

In the accompanying drawings, which are however merely intended to illustrate the principles of my invention without limiting the scope of the same, Figure 1 is a front elevation showing the safe and the cage with the latter raised into its elevated position; Fig. 2 is a vertical section of the same taken along the line II-II in Fig. 1; Fig. 3 is a view similar to Fig. 1 but with the cage dropped into the safe, and Fig. 4 is a view similar to Fig. 2 but showing the cage dropped into the safe.

The following is a detailed description of the drawings.

A represents a box safe formed of suitable steel and provided at its front with the usual doorway and door 1 fitted with the usual combination or time lock 2. The top of the safe is provided with an opening 3, preferably rectangular, and also preferably having its edges concavely curved as shown.

B is a cage whose solid top 4 is of safe steel and of proper dimensions to fit snugly into the opening 3 in the top of the safe A when the cage is dropped, the edges of the cage top 4 being convexedly curved to fit snugly into and seal with the edges of the opening 3. Thus no tool can be inserted to pry up the cage top, and obstructions will be forced aside and will not jam the cage when closing.

The bottom 5 of the cage B is of proper dimensions to pass through the opening 3, and said bottom 5 may be of metal or other material to match the bank furniture. When the cage is raised said bottom 5 is above or flush with the top of the safe, said safe being preferably of proper height to level with the permanent counter.

The sides 6 and the back 7 of said cage

are preferably made of crossed metal bars or lattice, and 8 represents vertical supporting bars at the corners connecting the top and bottom and bracing and strengthening the cage structure.

The cage B is supported in its elevated position by any convenient and readily releasable means. Thus I show a bar 9 slidably mounted in a horizontal position in a 10 slide bearing formed by a slot or opening 10 in the rear wall of the safe, so that said bar may be extended inwardly into the safe to engage the under side of the cage and support the latter in its elevated position, or 15 may be withdrawn outwardly to permit the cage to drop down into the safe.

Means are provided, workable from without the safe and preferably by the foot of the teller or other clerk, for retracting said 20 bar outwardly and thus causing the cage to drop down into the safe.

Thus, as a convenient and efficient means of effecting this function I provide the following mechanism.

25 11 is a bell crank lever whose angle is pivoted on the horizontal shaft 12. The upper, which is preferably the longer, end of said lever is pivotally connected to the outer end of the bar 9 but with sufficient 30 looseness so that said bar will not bind in its horizontal sliding movement. The lower end of the lever 11 is pivotally connected to the upper end of a bent lever 13 whose vertical portion extends down in the rear of 35 the safe and whose horizontal portion extends forwardly under the safe and at its end in front of the safe is provided with an upwardly extending boss or foot treadle 14. The operating lever 13 is supported by a 40 pair of slide bearings 15. 16 is a helical spring coiled about the operating lever 13 between the upper bearing 15 and the head of said lever, thus tending to force the lever 13 and the lever 11 into and hold them 45 in their raised positions, and thus tending to hold the bar 9 in its inwardly extended position wherein it supports the cage B.

17 is a stout steel boxing which conceals and protects the operating mechanism just 50 described and which is secured to back of the safe A in any convenient manner. The shaft 12 is journaled in said boxing and the bearings 15 are carried thereby.

If desired the horizontal portion of the 55 operating lever 13 may lead forwardly under the room floor with the treadle extending inconspicuously up through a hole in the floor.

It is evident that the teller or other clerk, 60 when attacked by robbers, may throw up his hands in apparent obedience to their commands, and at the same time step on the treadle, causing the cage to drop with its contents into the interior of the locked 65 safe.

Means are provided for locking the cage in its dropped position, said means being shown as follows. 18 is a metal loop or keeper depending from the bottom of the cage and adapted to be engaged by a pivoted 70 latch 19 mounted on the floor of the safe and held into engagement with said loop by means of a spring 20. It is evident that when the cage drops the latch will automatically engage the loop and lock the cage 75 stationary. As a means for releasing said locking latch, I provide a short hand lever 21 pivoted to the tail of the latch and extending forwardly within the safe, so that when, and only when, the safe door 1 has 80 been unlocked and opened, the latch may be released and the cage again elevated.

It is further important that an alarm, preferably audible, be given when a robbery is attempted. Thus I may provide an 85 electric alarm bell 22 connected in circuit with a battery 23, or other source of electric current, and with two contact arms 24 and 25 within the safe and normally resiliently held apart but adapted to be compressed together to complete the circuit 90 when the cage drops, thus giving the alarm.

For the sake of convenience of illustration I have shown the bell and battery within the boxing 17, but it will be understood that such alarm bell may be placed at any point within the banking room or building, or in the headquarters of the police or protective agency.

It is evident from the foregoing that my 100 device furnishes complete protection, and is of the greatest value for use in banks, financial institutions of all kinds, jewelry stores, and in short under any circumstances where money or other valuables must in the 105 course of business be kept displayed and are therefore subject to robbery.

In use my device may be placed at one side of the teller's window within the usual teller's cage, and the foot treadle may be 110 so placed that the release may be operated by the teller as he stands at the window.

Although, for the sake of clearness, I have minutely described the embodiment of my invention shown in the drawings, I do not wish to limit myself thereby, but claim:

1. In a protective device for the purposes described, the combination of a safe provided with an opening in its top, a counter board adapted when in its raised position to substantially occupy said opening, a closure for said opening above said counter board and connected to the latter so as to move in unison therewith, means for securing said counter board in its raised position, and means for releasing said securing means whereby said counter board automatically drops by gravity within said safe and said closure seals said opening.

2. In a protective device for the purposes 130

described, the combination of a safe provided with an opening in its top, a counter board adapted when in its raised position to substantially occupy said opening, a closure for said opening above said counter board and connected to the latter so as to move in unison therewith, means for securing said counter board in its raised position, means for releasing said securing means whereby said counter board automatically drops by gravity within said safe and said closure seals said opening, and means for locking said closure in said opening.

3. In a protective device for the purposes described, the combination of a safe having a lockable door in its wall and an opening in its top, a counter board adapted when in its raised position to substantially occupy said opening, a closure for said opening above said counter board and connected to the latter so as to move in unison therewith, means for securing said counter board in its raised position, means for releasing said securing means whereby said counter board drops within said safe and said closure seals said opening, means for locking said closure in said opening, and means whereby said locking means may be released only when said safe door is opened.

4. In a protective device for the purposes described, the combination of a safe provided with an opening in its top, a counter board adapted when in its raised position to substantially occupy said opening, a closure for said opening above said counter board and connected to the latter so as to move in unison therewith, means for securing said counter board in its raised position, and foot actuated means for releasing said securing means whereby said counter board drops within said safe and said closure seals said opening.

5. In a protective device for the purposes described, the combination of a safe provided with a lockable door in its wall and an opening in its top, a counter board adapted when in its raised position to substantially occupy said opening, a closure above said counter board and connected to the latter so as to move in unison therewith, means for securing said counter board in its raised position, foot actuated means for releasing said securing means whereby said counter board drops within said safe and said closure seals said opening, means for locking said closure in said opening, and means whereby said locking means may be released only when said safe door is opened.

6. In a protective device for the purposes described, the combination of a safe provided with an opening in its top, a cage movable vertically in relation to said opening, said cage being comprised of a bottom forming a counter board, a top forming a closure for said opening, and vertical walls connecting said top and bottom, one side of said cage being open, means for securing said cage in a raised position with the counter board substantially occupying said opening, and means whereby said cage automatically drops by gravity into the interior of said safe when said securing means are released, said counter board descending within said safe and said closure sealing said opening.

7. In a protective device for the purposes described, the combination of a safe provided with an opening in its top, a cage movable vertically in relation to said opening, said cage being comprised of a bottom forming a counter board, a top forming a closure for said opening and vertical walls connecting said top and bottom, one side of said cage being open, means for securing said cage in a raised position with the counter board substantially occupying said opening, means whereby said cage automatically drops by gravity into the interior of said safe when said securing means are released, said counter board descending within said safe and said closure sealing said opening, and means for locking said cage in its lowered position.

8. In a protective device for the purposes described, the combination of a safe provided with a lockable door in its wall and an opening in its top, a cage movable vertically in relation to said opening, said cage being comprised of a bottom forming a counter board, a top forming a closure and vertical walls connecting said top and bottom, one side of said cage being open, means for securing said cage in a raised position with the counter board substantially occupying said opening, means operated from without said safe for releasing said securing means whereby the cage drops, said counter board descending into said safe and said closure sealing said opening, means for locking said cage in its lowered position, and means whereby said locking means may be released only when the safe door is opened.

Signed at Pittsburgh, Pa., this 7th day of August, 1920.

JAMES F. COLLINS.
